UNITED STATES PATENT OFFICE

157,708

VACUUM CLEANER

John M. Sherrer, Wauconda, Ill., assignor to Clements Mfg. Co., Chicago, Ill., a corporation of Illinois

Application July 8, 1949, Serial No. 3,782

Term of patent 14 years

(Cl. D9—2)

To all whom it may concern:

Be it known that I, John M. Sherrer, a citizen of the United States, residing at Wauconda, in the county of Lake and State of Illinois, have invented a new, original, and ornamental Design for a Vacuum Cleaner, of which the following is a specification, reference being had to the accompanying drawing, forming part thereof.

In the drawing:

I claim:

The ornamental design for a vacuum cleaner, as shown.

JOHN M. SHERER.
